UNITED STATES PATENT OFFICE.

WILLIAM ASSHETON, OF ST. LOUIS, MISSOURI, ASSIGNOR TO THE ASSHETON DUPLICATING REGISTER COMPANY, OF ILLINOIS.

AUTOGRAPHIC REGISTER.

SPECIFICATION forming part of Letters Patent No. 429,495, dated June 3, 1890.

Application filed February 27, 1888. Serial No. 265,398. (No model.)

To all whom it may concern:

Be it known that I, WILLIAM ASSHETON, of St. Louis, Missouri, have made a new and useful Improvement in Autographic Registers, 5 of which the following is a full, clear, and exact description.

The novel features of the present construction will appear in the description and be noted in the claims, reference also being had 10 to the annexed drawings, making part of this specification, in which—

Figure 1 is a vertical longitudinal section of the improved register, the section being taken just within the near side of the register-case; Fig. 2, a front elevation of the register; Fig. 3, a vertical cross-section on the line 3 3 of Fig. 1; Fig. 4, a vertical cross-section on the line 4 4 of Fig. 1; Fig. 5, a vertical cross-section on the line 5 5 of Fig. 1; and 20 Fig. 6, a detail, being a section on the line 6 6 of Fig. 3.

The same letters of reference denote the same parts.

A represents the register-case. Its top a^1 is hinged at a^2 to the side a^3 of the case, and the lock a^4 is used to secure the free edge of the top to the side a^5 . Any other suitable means may be adopted to render the interior of the case accessible.

25 B represents the reel from which the paper webs C and D are delivered. The webs pass, first, respectively, over the roller-bearings E F, and thence, with the carbon sheet G, used in manifolding, interposed, the webs pass over the bearing-surface H, and then between the rolls I I'. After passing the rolls I I' the upper web C passes a knife J and then without the case, so that its projecting end c can, by drawing it over the knife, be separated from 35 the main portion of the web. The under web D is led from the rolls I I' to and is wound upon the reel K.

The means for effecting the movement of the webs and the operation of the device are 40 as follows: The reel B is journaled in suitable bearings b to enable the reel to rotate and the webs to be unwound whenever the ends of the webs are drawn upon. The web D, in initiating the operation, is wound upon 45 the reel K, so that when that reel is rotated

the web D shall be unwound from the reel B and drawn over the bearing-surface H and wound upon the reel K. The shaft k of the reel K is journaled in suitable bearings k' . L represents a pinion loose upon the shaft k . 55

M represents a rack-bar engaging with the pinion L and extending longitudinally within the case A, and having its end m sliding in a guide m' . A spring m^2 encircles the end m , bearing at one end against a shoulder m^3 upon the rack-bar and at the other end against the guide m' . When the rack-bar is moved toward the left-hand end of the case Fig. 1, the pinion L is rotated in the direction of the arrow l , Fig. 1, whereupon the pinion engages 65 with a pawl l' , which is pivoted to the reel K, and the reel K in consequence is rotated in the direction of the arrow l and the web D wound upon the reel K. The winding of the web D upon the reel K causes the upper 70 web C to be drawn along with it over the surface H, and its end c to be discharged from the case A, as shown in Fig. 1. On releasing the rack-bar the spring m^2 acts to return the rack-bar to its original position, during which 75 movement the pinion is free of the pawl l' , and the reel K remains stationary, and to insure its remaining stationary the reel may have a ratchet k^5 , Figs. 3 and 6, with which a pawl k^6 acts if the reel tends to turn. The rack-bar is moved from the outside of the register-case by means of the knob N. This knob 80 works in the slot a^5 in the case A, and is attached to the rack-bar at the inner side of the case side a^4 , and by moving the knob along 85 the slot a^5 the rack-bar is moved to effect the winding of the web D upon the reel K, as described, and on releasing the knob it is, through the agency of the spring m^2 , restored to the right-hand end of the slot a^5 , Fig. 1. 90 The movement of the rack-bar is further steadied by means of the arm O, which at o is jointed to the knob, at o' is hinged, and at o^2 is fastened to a shaft o^3 , which is journaled in bearings o^4 and is provided with the spring- 95 arms o^5 . For the arm O is thus also made, as the rack-bar is moved to wind the web upon the reel K, to relieve the tension upon the webs upon the reel B by causing the spring-arms o^5 , which bear upon the webs, to assume 100

the position indicated by the broken lines, Fig. 1.

The bearing-surface H is the support for the webs while being written upon.

5 I claim—

1. The combination, with the casing provided with the straight longitudinal slot a^5 , the straight rack-bar M, having the stem m, the knob N, the guide m' , and spring m^2 , of 10 the reel K, the pinion k, loose on the shaft of said reel, and the spring-controlled pawl l', substantially as specified.

2. The combination, with the casing having the straight longitudinal slot a^5 , the rack-bar,

the guide m' , the spring m^2 , the jointed arm 15 O, and springs o^5 , and knob N, of the rolls i^5 , the rollers E F, the reel B, the reel K, the pinion k, loose on the shaft of said reel, the spring-controlled pawl l', engaging said pinion, and the bearing-surface H, substantially as specified. 20

Witness my hand this 25th day of February, 1888.

WILLIAM ASSHETON.
